UNITED STATES PATENT OFFICE.

HARRY C. EARLE, OF BOSTON, MASSACHUSETTS, ASSIGNOR TO WALWORTH MANUFACTURING COMPANY, OF BOSTON, MASSACHUSETTS, A CORPORATION OF MASSACHUSETTS.

WRENCH.

1,134,948.

Specification of Letters Patent.

Patented Apr. 6, 1915.

Application filed January 29, 1913. Serial No. 745,485.

To all whom it may concern:

Be it known that I, HARRY C. EARLE, a citizen of the United States of America, and a resident of Boston, in the county of Suffolk and State of Massachusetts, have invented 5 certain new and useful Improvements in Wrenches, of which the following is a specification.

This invention relates to pipe wrenches 10 and has for its object the production of a wrench which will combine simplicity in construction and effectiveness in operation.

The invention consists primarily in forming integral with the body portion of the 15 wrench a pair of lateral projections having slots therein serving as guides for the movable jaw, which jaw is adapted to rock over the curved bottom of one of said slots, but is normally retained by a spring in a position 20 inclined to said body portion until pressure is applied to the latter to cause the jaws to bite upon the pipe, said spring tending to release said jaws from said pipe as soon as said pressure ceases.

25 The invention further consists in certain novel features of construction and arrangement of parts which will be fully understood by reference to the description of the drawings and to the claim hereinafter given.

30 Of the drawings: Figure 1 represents an elevation of a wrench embodying the features of the present invention. Fig. 2 is a rear view of the same. Fig. 3 is an enlarged section, the cutting plane being on line 3—3 35 on Fig. 1, and Fig. 4 is an enlarged section, the cutting plane being on line 4—4 on Fig. 1.

Similar characters designate like parts 40 throughout the several figures of the drawings.

In the drawings, 10 is the body portion of the wrench having formed integral therewith the fixed jaw 11 and the lateral projections 45 12 and 13. Both of these projections are bifurcated by having formed therein the guide slots 14 and 15, the outer end of the slot 14 being closed by a filling member 16, while the slot 15 is left open.

The shank 17 of the movable jaw 18 is 50 positioned in the slots 14 and 15 and is adapted to be adjusted lengthwise of the body portion 10 by means of the adjusting

nut 19 interposed between the projections 12 and 13, and the threads of which engage the threaded portion 20 of the shank 17.

55

The filling member 16 is secured to the bifurcated projection 12 by means of rivets 21 and to this filling member 16 is secured a flat spring 22 the free end of which extends through the slot 15 and bears upon 60 the outer face of the end of the shank 17, thereby normally retaining said shank in a position at a slight angle to the body portion 10 with the outer face of said shank contacting with the inner face of the filling 65 member 16 as indicated in dotted lines in Fig. 1.

During the adjustment of the movable jaw 18 one face of the adjusting nut 19 is adapted to bear upon the inner face of the 70 projection 12 at a point adjacent to the body portion 10 while the opposite face of said nut bears against the inner face of the projection 13 near its outer end. When this jaw has been properly adjusted and has been 75 placed upon a pipe or other article, any further adjustment of the nut 19 will cause the shank 17 of the jaw 18 to be moved against the tension of the spring 22 into a position more nearly parallel with the body 80 portion 10, the inner face of the nut 19 then bearing against the face of the projection 12 on all sides of the shank 17. It is obvious that most of the adjustment of the jaw 18 is performed while its shank is in the angular position described and that owing to 85 the fact that the nut is only contacting at two points with the projections 12 and 13 a very easy movement of said jaw is insured from the fact that the frictional contact is 90 reduced to a minimum.

The bottom of the slot 14 is curved inwardly toward the fixed jaw 11 as indicated at 23 in Fig. 1, thereby providing means whereby the movable jaw 18 may be rocked 95 relative to the body portion 10 to secure a firmer grip upon the pipe 24.

It is obvious that when the wrench is in use the handle or body portion 10 is moved in the direction of the arrow *a* on Fig. 1, 100 and this movement of the body portion relative to the movable jaw 18 causes the space between the fixed and movable jaws to be decreased and the teeth of said jaws to be

forced into the surface of the pipe or other article and a firm grip thereon to be secured. As soon as pressure upon the handle 10 is removed, the action of the spring 22 5 upon the movable jaw 18 will cause the jaws to be released from the pipe 24 so that the wrench may be moved into a new position upon the pipe preparatory to a repetition of the gripping action thereon. The width 10 of the nut 19 is less than the space between the projections 12 and 13 in order to permit the rocking movement of the jaw 18, said rocking movement being limited by the contact of the outer end of the nut with the 15 inner face of the projection 13.

The construction shown and described herein forms a very effective wrench of great simplicity, while, by making the projections 12 and 13 integral with the body portion a 20 very strong device is secured that may be subjected to great strains, it being possible to construct the entire body portion of steel forging thereby dispensing with castings and all pivotal connections which tend to 25 weaken the wrenches now in general use.

It is believed that the operation and many

advantages of the invention will be fully understood from the foregoing description.

Having thus described my invention, I claim:

In a device of the class described, the combination of a body portion having an integral fixed jaw and two lateral projections slotted so as to form a curved surface at the bottom of the slots, a movable jaw 35 having a threaded shank passing through said slots, an adjusting nut on the shank loosely engaged by said projections, a filling member to close the slot in the projection nearer the jaws and form a passage in which 40 said shank is free to move toward and from said curved bottom, and a spring mounted on said member and constructed so that its free end will be positioned in the slot of the projection farther from the jaws and bear 45 on the outer face of said threaded shank.

Signed by me at 4 Post Office Sq., Boston, Mass., this 18th day of January, 1913.

HARRY C. EARLE.
